UNITED STATES PATENT OFFICE.

ALEXANDER FINDLY McGIRR, OF METCALFE, ONTARIO, CANADA.

BARN.

1,336,471.

Specification of Letters Patent. Patented Apr. 13, 1920.

Application filed November 10, 1916. Serial No. 130,634.

To all whom it may concern:

Be it known that I, ALEXANDER FINDLY McGIRR, a subject of the King of Great Britain, and resident of Metcalfe, in the 5 Province of Ontario, Dominion of Canada, have invented certain new and useful Improvements in Barns, of which the following is a specification.

This invention relates to improvements 10 in barns and the objects of the invention are to eliminate all transversely and longitudinally extending beams which may materially affect the capacity of the barn, to permit of the walls of the barn being adequately strengthened so that they may 15 resist the internal pressure due to produce stored in the barn and at the same time permit of the structure adequately withstanding wind pressure. Further objects are to 20 permit of the joints of the sections of the rafters being suitably secured together so that strength and durability together with the desired resiliency may be given thereto and generally to adapt the several parts to 25 better perform the functions required of them.

With the above and other objects in view the invention consists essentially of the improved construction particularly described 30 and set forth in the following specification and accompanying drawings forming part of the same.

In the drawings,

Figure 1 is a transverse section of the im- 35 proved barn.

Fig. 2 is a fragmentary longitudinal sectional elevation of the same.

Fig. 3 is a fragmentary side elevation of 40 the trusses showing the means of supporting the purlin plates therefrom.

Fig. 4 is a side elevation of a truss designed to strengthen the purlin plates.

Fig. 5 is a plan view of the brace located at the corners of the barn.

Like characters of reference refer to like parts in the several figures.

Referring to the drawings, A represents the improved barn comprising the foundation B which may be made of concrete or the 50 like on which the frame C is built. The frame C consists of a plurality of uprights 10 located at the corners of the barn and intermediate of the length and ends thereof, being operatively connected by the longitudinally extending braces 11 to which the 55 clap board or the like is secured. These

walls are strengthened by a plurality of trusses D equidistantly spaced from each other and secured to the several uprights 10 in a manner to be made clear hereafter. 60

The uprights 10 are operatively connected at their upper end by a wall plate 12 adapted to carry the rafters which are formed in two sections 13 and 14, the former of which is notched as shown at 15 so that 65 it may intimately engage with the said wall plate.

Any tendency of the section 13 of the rafters falling inwardly is provided for by means of the trusses D each of which 70 comprises a vertical member 15^a inclined slightly at the top toward the uprights 10, the lower end being connected by the plate 16 to the joist 17, while the upper end is connected by the angularly disposed strut 75 18 to the plate 19 which is rigidly connected to the said upright. The lower portion of the truss frame is completed by the angularly disposed struts 20, arranged in zig-zag formation across the frame and operatively 80 connected at the ends to the upright 10 and the member 15^a respectively.

The upper end of the truss frame D is completed by a pair of vertically extending and angularly disposed members 21 and 85 22 which converge toward the top and are suitably secured to the plate 23.

The upper end of the member 22 is provided with a resilient adjustable wedge shaped piece 24 suitably secured thereto 90 and adapted to engage with the purlin plate 25 extending longitudinally of the barn and supporting the upper end of the lower sections 13 of the rafters. The wedge piece 24 is of skeleton formation so that the desired 95 resiliency is obtained and consequently a slight yield is given to the purlin plates 25 when stress is exerted thereon. By using this wedge piece any sag can be taken up and there is less liability of collapse of the roof 100 of the barn than is otherwise likely to take place if the purlin plates 25 were rigidly attached to the struts D and excessive pressure brought to bear upon the same.

The adjacent ends of the upper sections 105 of the rafter are butt joined and secured by the frames 26 which are substantially diamond shaped and suitably secured in position by bolts, the lateral members of the said frame embracing a substantially U-shaped 110 member 27 which is designed to act as a strut giving rigidity to the frame, and at the

- same time permitting of the desired resiliency so that a certain yield will be obtained and there is no liability of the roof becoming excessively strained.
- 5 The purlin plates 25 are adequately strengthened by longitudinally extending trusses 28 which are operatively supported by the upper end of the truss frame D. The trusses 28 consist of a substantially straight 10 member 29 coacting with the purlin plates 25 and operatively connected to a member 30, the center portion of which is substantially parallel to the member 29 but with its ends offset, the said members embracing a 15 substantially W-shaped strut member 31 designed to give rigidity and desired resiliency to the said truss.
- The ends of the barn are suitably strengthened by the truss frame E located intermediate 20 of the breadth thereof and consisting of vertical disposed members 32 inclined inwardly at the top toward the end of the barn and being operatively connected by the angularly disposed members 33 to the wall 25 plate 12, the frame being completed by a plurality of angularly disposed truss members 34 arranged in zig-zag forms and operatively secured to the member 32 and the upright 10.
- 30 The truss 28 is operatively connected by the sway rods 35 to the wall plate 12. The corners of the barn are suitably strengthened by angularly disposed braces 36 which are secured to the side and end walls of the 35 barn by any suitable means. The purlins 37 are secured to the outer face of the sections 13 and 14 of the rafters when the clap board or like roofing of the barn may be secured in position.

From the foregoing description it will be 40 readily appreciated that a barn constructed in this manner will have the desired strength to carry produce stored therein, and at the same time to withstand the external wind or like pressure, while by the arrangement of 45 the several trusses, transverse and longitudinally extending beams are entirely dispensed with so that capacity of the barn is a maximum.

As many changes could be made in the 50 above construction, and many apparently widely different embodiments of my invention, within the scope of the claims, constructed without departing from the spirit or scope thereof, it is intended that all matter 55 contained in the accompanying specification and drawings shall be interpreted as illustrative and not in a limiting sense.

What I claim as my invention is:

In a structure of the class described, a 60 joist, an upright at the end thereof, a rafter supported by said upright, a vertical member connected to the joist and spaced from the said upright, diagonal struts connecting said upright and vertical member, a pair of 65 converging members connected respectively to said upright and vertical member, at their lower ends, and connected together at their upper ends, a resilient adjustable wedge-shaped piece on the upper ends of the converging members, and a purlin supported by the wedge-shaped piece, designed to support 70 the rafter.

In witness whereof I have hereunto set my hand in the presence of a witness.

ALEXANDER FINDLY McGIRR.
